UNITED STATES PATENT OFFICE.

DON COLE, OF CHICAGO, ILLINOIS, ASSIGNOR TO WAUKESHA MOTOR CO., OF WAUKESHA,
WISCONSIN, A CORPORATION OF WISCONSIN.

INTERNAL-COMBUSTION ENGINE.

1,314,948.

Specification of Letters Patent. Patented Sept. 2, 1919.

Application filed January 4, 1917. Serial No. 140,523.

To all whom it may concern:

Be it known that I, DON COLE, a citizen of the United States, residing at Chicago, in the county of Cook and State of Illinois, 5 have invented a certain new and useful Improvement in Internal-Combustion Engines, of which the following is a full, clear, concise, and exact description, reference being had to the accompanying drawings, forming 10 a part of this specification.

My invention relates to internal combustion engines and is concerned with the flow of the combustible mixture from the carbureter to the engine cylinder or cylinders.

15 Notwithstanding the efficient design of carbureting apparatus for producing and delivering a proportioned mixture of air and fuel, such as gasoline, difficulty is frequently encountered in getting the mixture thus formed

20 to the engine cylinder or cylinders in the condition originally determined by the carbureter. In other words, even though the carbureting apparatus may be highly efficient, such efficiency is frequently lost or 25 greatly decreased during the passage of the mixture from the carbureter to the engine cylinder or cylinders. The disposition of the usual manual throttle control at the outlet of the carbureter is a hindrance to the

30 continued perfection of the mixture by reason of its mechanical effect thereon, first because it forms an irregular restriction passing beyond which the combustible mixture tends to expand, and second, by reason of its 35 physical formation it tends to throw the mixture forcibly against the side walls of the passageway leading to the engine cylinder or cylinders. In the case of the first effect the expansion causes a reduction in speed

40 and the tendency is for very small particles of fuel, which would otherwise be carried along with the current, to be deposited on the walls of the passageway, thus annihilating the proportion carefully determined 45 at the carbureter in the first instance and causing choking of the engine due to excessive richness of mixture when the position of throttle is subsequently changed, this deposited fuel being suddenly drawn to the

50 cylinder or cylinders. In the second effect the deposit of liquid fuel on the walls of the passageway is due to the difference in weight between the air and the particles of unvaporized fuel.

55 I therefore dispose a so-called Venturi

tube, well known in and of itself to those skilled in the art, between the carbureter and the engine cylinder or cylinders so as to give an impetus to the mixture flowing therethrough after leaving the carbureter, to effect mechanical mixture, and to send on to the engine cylinder or cylinders a proper mixture of air and fuel proportioned as determined by the carbureter and homogeneous throughout. In this way, any particle of 60 liquid fuel which remains unvaporized upon leaving the carbureter will either finally vaporize or will at least be kept suspended in the current to be completely vaporized as it nears and enters the hot cylinder or cylinders of the engine. 70

I shall describe my invention in a more detailed way by reference to the accompanying drawing which is a longitudinal sectional view of a carbureter supplemented by the 75 passage to the engine cylinder or cylinders.

In this drawing the carbureter casing 1 is provided at the bottom with the primary air inlet 2 which leads to the Venturi tube 3 in which a fuel nozzle 4 is disposed, this fuel nozzle being supported on a spider 5 through which a passageway 6 is formed for the connection of the fuel nozzle with a suitable source of supply of liquid fuel, not shown. It may be assumed that the normal level of 80 fuel is on the line $x-x$, as determined, for instance, by a float chamber. The Venturi tube 3 extends into the carbureting chamber 7 which is provided with a secondary air inlet 8 normally closed by a valve 9 mounted 85 upon a stem 10 guided in the spider 11 and the adjustable plug 12, a spring 13 being disposed between the adjustable plug 12 and the valve 9. 90

The carbureter outlet is indicated at 14, 95 this outlet being of tubular form and being controlled by means of a butterfly throttle 15 mounted upon a stem 16 journaled in the casing 1 and extending diametrically across the outlet. The Venturi tube member 16' 100 is secured to the flange 17 surrounding the carbureter outlet 14 and has its Venturi passageway therethrough in alinement with and co-incident with the outlet 14, as illustrated. This Venturi tube member 16' 105 extends into the pipe 18 which leads to the engine cylinder or cylinders, this pipe being a manifold in the case of a multi-cylinder engine.

It will now be clear that suction is trans-

mitted from the engine cylinder or cylinders to the carbureter and that, responsive to this suction, air will be drawn in through the primary air inlet 2, gasoline being fed from the nozzle 4 responsive to such suction and to the aspirating effect of the inflowing air. Diluting air is admitted through the secondary air inlet 8 on the higher suctions. The usual throttle control is familiar to those skilled in the art and needs no further description here. Obviously, the throttle 15 controls the flow of combustible mixture from the carbureter to the engine cylinder or cylinders and, after passing through the outlet 14 of the carbureter, the combustible mixture will pass through the Venturi tube 16', in the manner and with the effect pointed out above, and on to the engine cylinder or cylinders.

20 I claim:

1. In combination, an internal combustion engine, a carbureter connected therewith, a throttle between said engine and said carbureter, and a Venturi tube between said throttle and said engine.

2. In combination, an internal combustion engine, a carbureting chamber connected therewith, a Venturi tube leading to said carbureting chamber, means for admitting air and fuel to said Venturi tube, a throttle between said carbureting chamber and said engine, and a Venturi tube between said throttle and said engine,

between said carbureting chamber and said engine, and a Venturi tube between said throttle and said engine.

3. In combination, an internal combustion engine, a carbureter connected therewith, a butterfly throttle between said engine and said carbureter, and a Venturi tube between said throttle and said engine.

4. In combination, an internal combustion engine, a carbureting chamber connected therewith, a Venturi tube leading to said carbureting chamber, means for admitting air and fuel to said Venturi tube, a butterfly throttle between said carbureting chamber and said engine, and a Venturi tube between said throttle and said engine.

5. In combination, an internal combustion engine, a carbureting chamber connected therewith, a Venturi tube leading to said carbureting chamber, means for admitting air and fuel to said Venturi tube, a throttle between said carbureting chamber and said engine, and a Venturi tube between said throttle and said engine, said last named Venturi tube being clamped between the carbureter and the pipe to the engine.

In witnesses whereof I hereunto subscribe my name this 29th day of December, A. D. 1916.

DON COLE.
